UNITED STATES PATENT OFFICE.

FRED BERONIO, OF SAN FRANCISCO, CALIFORNIA, ASSIGNOR TO LEVI STRAUSS & CO.,
A CORPORATION OF CALIFORNIA.

COVERALLS.

1,390,010.

Specification of Letters Patent. Patented Sept. 6, 1921.

Application filed December 4, 1919. Serial No. 342,415.

To all whom it may concern:

Be it known that I, FRED BERONIO, a citizen of the United States, residing at San Francisco, in the county of San Francisco 5 and State of California, have invented new and useful Improvements in Coveralls, of which the following is a specification.

This invention relates to a child's garment. It is the particular object of the present invention to provide a child's garment in the 10 nature of a coverall, which is manufactured in a manner to make the garment easily adapted for use by either girls or boys.

The present invention contemplates the 15 use of a garment having a jacket portion formed integral with a pair of long trousers, the front of the trousers being formed with a "fly" and an opening which may be rendered operative if desired, or which may 20 remain closed.

Referring more particularly to the drawing:—

Figure 1 is a view in elevation showing the 25 garment applied to a figure.

Fig. 2 is a fragmentary view in front elevation, showing the trouser portion of the 30 garment and more clearly disclosing the lock stitch seam extending down the front of the trousers.

Fig. 3 is a fragmentary view similar to Fig. 2 illustrating a portion of the front of the trousers torn away to more clearly show the "fly" construction.

Referring more particularly to the drawings, 35 10 indicates a waist of any suitable design and which is formed integral with trousers 11. The waist and trousers are preferably formed of continuous lengths of fabric and the waist line is defined by a belt 40 12 permanently stitched to the goods. The front portion of the trousers is formed of two panels A and B, and these panels are stitched together down a median line with lock stitches, as indicated at 13. These 45 stitches continue to the crotch of the trousers. After the stitching has been made, a "fly" member 14 or flap portion, as it might be termed, is secured in the rear of the seam 13 at a point near the crotch, as more clearly 50 shown in Fig. 2. This member 14 is fastened at its upper and lower ends by transverse stitching 15. This stitching is spaced a distance from each other agreeing substantially with the length of the flap. The 55 stitching is provided for a two-fold pur-

pose. First, to secure the flap in position, and secondly, to stitch across the lock seam 13 to prevent the stitching of the seam 13 from running in the event that the stitching between the transverse stitches is ripped out. 60

In the operation of the present invention, the garment is formed as is clearly shown in the drawing and is placed on the market with the seam 13 intact throughout its length. When the garments are sold, they 65 may be bought for the use of boys or girls. In one event, the stitching 13 will not be molested, and in the other event, the length of stitching between the transverse stitches 15 will be ripped away to form an opening 70 16. This opening will, of course, be covered by the flap 14. It will thus be seen that by the simple provision of the transverse stitches securing the flap and crossing the lock stitch seam 13, it will be possible to permit the intervening stitching between the 75 transverse stitches to be cut away without danger of the further unraveling of the stitches in the seam and at the same time securing the flap in position. 80

While I have shown a preferred form of my invention, as now known to me, it will be understood that various changes might be made in the combination, construction, and arrangement of parts by those skilled in the 85 art without departing from the spirit of the invention.

Having thus described my invention, what I claim and desire to secure by Letters Patent is:

1. In a garment of the character described, the combination with two front members normally stitched together vertically by a double seam, of a semi-circular supplemental flap member having the 90 straight edge fixed parallel and contiguous to the vertical seam, and the curved edge extending across and beyond said seam, and transverse stitching securing the upper and lower ends of the curved edge across the 95 main vertical seam, to allow the intervening length of seam after being ripped open to be shielded.

2. In a garment of the class described, a pair of trousers having front panels normally stitched together along contiguous vertical edges and said seam substantially extending from the belt to the crotch of said garment, a flap member stitched to the garment in the back of said seam, and at a point 100 105 110

adjacent the crotch of the garment, said flap being secured by transverse stitching intersecting the aforesaid vertical seam, and engaging the opposite ends of the flap whereby 5 the flap will be held in the rear of the portion of the vertical seam between the transverse seams, and in a manner to shield an opening which would be formed by ripping the intervening vertical seam between the 10 transverse seams, said transverse stitching

at the same time preventing the further opening of the vertical seam after it had been ripped.

In testimony whereof I have hereunto set my hand in the presence of two subscribing 15 witnesses.

FRED BERONIO.
